US00D983355S

(12) **United States Design Patent** (10) **Patent No.:** **US D983,355 S**
Wu (45) **Date of Patent:** **** Apr. 11, 2023**

(54) **RESPIRATION DEVICE**

(71) Applicant: **Tecmen Electronics Co., Ltd.**, Jiangsu (CN)

(72) Inventor: **Ziqian Wu**, Nanjing (CN)

(73) Assignee: **Tecmen Electronics Co., Ltd.**, Nanjing (CN)

(**) Term: **15 Years**

(21) Appl. No.: **29/797,490**

(22) Filed: **Jun. 30, 2021**

(30) **Foreign Application Priority Data**

Mar. 18, 2021 (CN) 202130146157.6

(51) **LOC (14) Cl.** **29-02**

(52) **U.S. Cl.**

USPC **D24/110**

Assistant Examiner — Michael Hoffman

(57) **CLAIM**

The ornamental design for a respiration device, as shown and described.

DESCRIPTION

FIG. 1 is a front perspective view of a respiration device, showing my new design;

FIG. 2 is a front elevation view of the respiration device of FIG. 1;

FIG. 3 is a rear elevation view of the respiration device of FIG. 1;

FIG. 4 is a right side view of the respiration device of FIG. 1;

FIG. 5 is a left side view of the respiration device of FIG. 1; FIG. 6 is a top view of the respiration device of FIG. 1; and, FIG. 7 is a bottom view of the respiration device of FIG. 1. The broken lines shown in the drawings represent portions of the respiration device that form no part of the claimed design.

1 Claim, 5 Drawing Sheets
